UNITED STATES PATENT OFFICE.

EARLE M. WOODEN, OF NEW YORK, N. Y., ASSIGNOR TO THE PERFECTOGRAPH MANUFACTURING COMPANY, OF NEW YORK, N. Y., A CORPORATION OF DELAWARE.

AUTOMATIC LOOP-MAKER FOR MOVING-PICTURE FILMS.

1,196,063.

Specification of Letters Patent. Patented Aug. 29, 1916.

Application filed March 3, 1915. Serial No. 11,739.

To all whom it may concern:

Be it known that I, EARLE M. WOODEN, a citizen of the United States, and a resident of the borough of Manhattan of the city of New York, in the State of New York, have invented certain new and useful Improvements in Automatic Loop-Makers for Moving-Picture Films, of which the following is a specification, reference being had to the accompanying drawings, forming a part hereof.

In the operation of moving picture machines, it is well recognized that the delay incidental to the placing of a fresh reel in the magazine and the threading of the film through the machine and the formation of the loops for compensation of the intermittent driving motion, is very objectionable to the audience and efforts have been made to shorten the time required for these preliminary settings by the operator.

It is the general object of this invention to shorten the time for placing the film in position for the commencement of the exhibition by providing devices which will automatically form the required loops in the film without any manipulation on the part of the operator.

In machines embodying the invention the operator need only pass the film around the usual sprockets and guide rolls and then set the prime mover in motion, whereupon the required loops in the film will be formed and the projection of the images follow, such operations as are required to bring about these effects being carried on automatically.

In the preferred form of the invention, which is illustrated in the accompanying drawings by way of example, the upper sprocket is rotated momentarily to produce the upper loop, the mechanism for producing the intermittent motion being at rest during this time, and the lower sprocket remains idle momentarily to make the lower loop, all of the driving means for the respective sprockets and the mechanism for imparting the intermittent motion, being restored automatically to normal operating positions immediately upon the formation of loops of predetermined length.

Reference is now to be had to the accompanying drawings for a detailed description of the invention, in which—

55 Figure 1 is a fragmentary view in side

elevation of the housing for the film and the driving sprockets, the parts being shown somewhat conventionally. Fig. 2 is a view in side elevation of the devices for driving the various sprockets and showing the application thereto of an automatic loop maker, embodying the present invention, the view being taken along the plane indicated by the line 2—2 of Fig. 3 and looking in the direction of the arrows. Fig. 3 is a view partly in elevation and partly in section of the devices illustrated in Figs. 1 and 2 and showing particularly the relative arrangement of such devices. Fig. 4 is a view somewhat similar to Fig. 2, but showing the 60 automatic loop maker in position to form the upper loop. Fig. 5 is a fragmentary view in plan of the upper feed sprocket and the loop maker, the parts being shown in normal operating position. Fig. 6 is a 65 view similar to Fig. 5 but showing the loop maker in position to cause the formation of the upper loop.

As indicated particularly in Fig. 3, the housing *a* is provided with a partition *a'* by which the upper sprocket *b*, the lower sprocket *c* and the intermittently actuated feeding sprocket *d* are relatively exposed to permit the film *e* to be threaded through the machine by the operator, while all of the actuating devices are incased completely in the other portion of the housing and thereby protected from injury, dust, etc. The usual co-operating guide rolls *f* may be mounted in operative relation to the sprockets *b* and *c* or to the window plate *a²* across the aperture *a³* of which the film is passed to permit the projection of the image. It is quite evident that a great deal of time in preparing the film for exhibition might be 70 saved if it were not necessary for the operator, after passing the film through the slot *a⁴* of the housing *a*, to form, with some care, the upper loop *e'* and the lower loop *e* for compensation of the intermittent 75 driving motion imparted by the sprocket *d*. In the present invention it is proposed that the operator shall pass the film quickly through the slot *a⁴* and around the several sprockets *b*, *c* and *d*, and the guide rolls *f* 80 without forming the required loops but permitting the film to rest substantially taut, as indicated by dotted lines in Fig. 1. The devices now to be described, upon operation of the prime mover, will then permit rela- 85 90 95 100 105 110

tive movement first, between the sprocket b and the intermittently actuated sprocket d and second, between the sprocket c and said sprocket d , the travel of the film through the machine in the usual manner being continued immediately upon the formation of the upper and lower loops e' and e'' .

While the present improvements are not concerned with the driving mechanism for the film, it will be conducive to a clearer understanding of the application of the improved loop maker to these devices to point out generally their arrangement with respect to each other, as illustrated in the accompanying drawings. The upper sprocket b is carried on a shaft b' which passes through and is journaled, as at b^2 , in the partition plate a' of the housing a , the shaft being threaded on its inner end and carrying a pinion b^3 , to which rotation is imparted through an idler g which, in turn, may be driven by a spur gear h carried on the inner end of the rotatable driving shaft h' deriving its movement from a hand crank h^2 or any other available source of power. The main driving gear h also engages a pinion i fixed on a short shaft i' which may be journaled in an arm k , hereinafter to be described more particularly. On the free end of the stub shaft i' is keyed a large bevel gear i^2 on the face of which is formed a bevel pinion i^3 . The large bevel gear i^2 meshes normally with a bevel pinion l carried on an idle spur gear l' which meshes, in turn, with a second spur gear m , the rotation of which is transmitted to the intermittently actuated driving devices (not illustrated), but indicated as being mounted in a housing n , through a flexible shaft m' . From the intermittently actuated mechanism referred to, the driving sprocket d receives its movement. The bevel pinion i^3 on the large bevel gear i^2 , meshes with a bevel pinion o , the rotation of which is normally imparted through a slideable shaft o' and pinion o^2 on the lower end thereof, to a bevel gear p secured to the shaft p' of the lower sprocket c . The mechanism thus far described may be of any approved character, in so far as the known functions thereof are concerned, and the somewhat conventional showing of this mechanism is made only to enable the operation of the loop maker to be understood.

The arm k which not only supports the stub shaft i' , but also carries bearing brackets k' and k'' for the transmission shaft o' , is mounted to oscillate about a cylindrical bearing piece a' which may be carried on the partition plate a' , and this arm may be swung about its supporting bearing a' , in one direction, by manual manipulation of a pull-rod q , the free end of which projects beyond the wall of the housing a . Movement of the arm k to its normal position

after such manipulation may be brought about by a spring r operatively interposed between the arm k and some fixed abutment, such as the end of the shaft h' . One effect of swinging the arm k about its bearing a' is to move the large bevel gear i^2 out of engagement with the pinion l , so that no movement can be imparted through the gearing hereinbefore described, to the intermittently actuated devices which are contained within the casing n . Accordingly, when the parts are thus moved to the position shown in Fig. 4, rotation of the shaft h' causes rotation of the upper sprocket b , but the intermittently actuated sprocket d remains at rest so long as the arm k is maintained in this position. This relative rotation of the sprocket b with respect to the sprocket d makes the upper loop e' immediately, and so far as this loop is concerned it is necessary only to restore the intermittently actuated sprocket d to normal running conditions when the loop e' is of sufficient length, to carry on the usual exhibition of the film. The devices for insuring the restoration of normal operating conditions for the intermittently actuated sprocket d immediately upon the making of a loop e' of sufficient length, are found in the present embodiment, in a spring-pressed latch k^3 mounted pivotally on the upper end of the arm k and adapted to engage the nose a^5 of a catch a^6 conveniently secured to the partition plate a' , whenever the arm k is swung to the position shown in Fig. 4. On the tail of the latch k^3 is pivotally secured a half nut s , the exposed threads of which are forced into engagement with the threads on the end of the shaft b' when the arm k is rocked to interrupt the driving transmission of the intermittently actuated sprocket d . Rotation of the shaft b' when the prime mover shaft h' is rotated, serves to thread the half nut s along the threads of the shaft so as to rock the latch k^3 about its supporting pivot pin k^4 and finally move the nose of the latch out of engagement with the nose of the catch a^6 . The threaded portion of the shaft b' is so arranged with respect to the threads of the half nut s and the latch k^3 as to release the latch and permit the restoration of normal operating conditions for the intermittently actuated sprocket d immediately upon the formation of an upper loop e' of predetermined length.

In describing the operation whereby the lower loop is formed, it is important to remember that the oscillating arm k is first moved by manual manipulation of the pull-rod q , before the film is threaded through the machine. As soon as the latch k^3 engages the nose a^5 , the operator may release the pull-rod q and the parts will remain in locked position with the intermittent feed interrupted. Auxiliary mechanism, of the

character now to be described, is employed for permitting relative rotation between the intermittent feed and the lower sprocket *c* for the formation of the lower loop. This mechanism comprises generally a threaded cap *o*³ on which is formed the pinion *o* and in which is seated the upper end of the transmission shaft *o'*, the latter being threaded, as at *o*⁴, to coöperate with the threads of the cap *o*³. By reason of this threaded engagement it will be evident that axial movement of the shaft *o'* with respect to the cap *o*³ will cause rotative movement of the shaft. The shaft *o'* may conveniently be moved axially with respect to the cap *o*³ through the medium of a forked slide *t* which partially embraces the shaft and bears against a washer *o*⁵ fixed thereon, the other end of the forked member being pivotally attached, as at *t'*, to an elbow lever *q'*, mounted pivotally, as at *k*⁵, on the oscillating arm *k* and connected to the pull rod *q*. It should now be evident that when the arm *k* is oscillated to the position above referred to, the shaft *o'* will be moved axially with respect to the cap *o*³. Axial movement of the shaft *o'* can only result where there is relative rotation between this shaft and the cap *o*³ since these two elements are in threaded engagement. The shaft *o'* cannot rotate since it is held against rotation by the actuating devices but the cap *o*³ is free to rotate, being merely held against axial movement. Axial movement of a non-rotatable member with respect to a member which is free to rotate and which is engaged with the first named member through threads of steep pitch necessarily results in the rotation of the second named member. The film is then threaded through the machine and drawn taut over the upper and lower sprockets. Immediately upon the reengagement of the bevel gear *i*² with the pinion *z*, the cap *o*³ will be rotated. Rotation of this cap will then serve to move the shaft *o'* axially within the cap until the upper end of the shaft seats therein. While this shaft *o'* is being moved axially in this manner, it will be understood that no rotative movement is transmitted to the sprocket *c* although the sprocket *d* is meanwhile rotating and feeding the film forward. The relative movement between the intermittent feed and the lower sprocket *c* which is thus produced, results in the formation automatically of the lower loop. As soon as the shaft *o'* is threaded fully into the cap *o*³, rotation of the sprocket *c* is produced and the exhibition of the film in the usual manner is carried on. It is to be understood that the automatic loop making mechanism has its various elements so related to each other and to the sprockets as to harmonize in their respective actions and insure the formation of loops of proper length and the resumption

automatically of normal operating conditions immediately upon the formation of such loops. The principal object of the invention being to reduce the time required for the threading of a film through a machine for the commencement of the exhibition, it will be appreciated that the time which is required for the formation of the loops is to be reduced to a minimum and the travel of the film through the machine is to be initiated as nearly coincident with the formation of the loops as is possible.

Other means for permitting relative movement of the sprockets of a machine for forming the loops automatically before the commencement of the exhibition and for feeding the film forward immediately upon the formation of the loops, will suggest themselves to those skilled in the art, but it is to be understood that the substitution of mechanical equivalents for the elements herein illustrated or mere re-arrangements of the parts shown are to be deemed within the spirit of this invention provided they fall within the scope of the appended claims.

I claim as my invention:

1. In a moving picture machine, driving mechanism for the film including upper and lower continuously operable sprockets and an intermittent feed, means to disconnect the intermittent feed momentarily from the driving mechanism, whereby continued rotation of the upper sprocket forms a loop in the film between the upper sprocket and intermittent feed, and devices to hold the lower sprocket against rotative movement with respect to the intermittent feed to make a loop in the film between it and the intermittent feed.
2. In a moving picture machine, driving mechanism for the film including upper and lower continuously moving sprockets and an intermittent feed, means under the control of the operator to disconnect the intermittent feed momentarily from the driving mechanism, and devices actuated by said last named means for permitting differential rotation between the intermittent feed and the lower sprocket to form a loop between the lower sprocket and the intermittent feed, continued rotation of the upper sprocket serving to form a loop between it and the intermittent feed.
3. In a moving picture machine, driving mechanism for the film including upper and lower continuously operable sprockets and an intermittent feed, means to disconnect the intermittent feed momentarily from the driving mechanism, whereby continued rotation of the upper sprocket forms a loop in the film between the upper sprocket and the intermittent feed, devices to hold the lower sprocket against rotation with respect to the intermittent feed to permit differential movement between it and

- the intermittent feed to form the lower loop between the lower sprocket and the intermittent feed, and means to return automatically all of the parts to normal operating positions for the projection of the film upon the formation of the loops.
4. In a moving picture machine, driving mechanism for the film including upper and lower continuously operable sprockets and an intermittent feed, transmission devices operatively connected between the driving mechanism and the intermittent feed, an oscillating arm on which certain of said transmission devices are mounted, said arm being susceptible of oscillation by the operator to interrupt the transmission of power to the intermittent feed, rotation of the upper sprocket forming a loop in the film between it and the intermittent feed, means to return the arm to operative position, and devices to rotate the intermittent feed, momentarily upon reconnection, with respect to the lower sprocket to form a loop between it and the intermittent feed.
5. In a moving picture machine, driving mechanism for the film including upper and lower continuously operable sprockets and an intermittent feed, transmission devices operatively connected between the driving mechanism and the intermittent feed, an oscillating arm on which certain of said transmission devices are mounted, said arm being susceptible of oscillation by the operator to interrupt the transmission of power to the intermittent feed, rotation of the upper sprocket forming a loop in the film between it and the intermittent feed, means to return the arm to operative position, and devices to rotate the intermittent feed, momentarily upon reconnection, with respect to the lower sprocket to form a loop between it and the intermittent feed.
6. In a moving picture machine, driving mechanism for the film including upper and lower continuously operable sprockets and an intermittent feed, transmission devices operatively interposed between the intermittent feed and the driving mechanism, a movable arm on which certain of said transmission devices are carried, a pull-rod carried by the arm to facilitate movement thereof by the operator to interrupt the transmission of power to the intermittent feed, a latch carried by the arm to maintain it in the last named position, transmission devices operatively disposed between the driving mechanism and the lower sprocket including a threaded shaft slidable axially, an interiorly threaded cap carried on the threaded portion of the shaft, means under the control of the operator to effect relative axial movement between the shaft and the cap to permit rotation of the intermittent feed with respect to the lower sprocket to form a loop in the film between it and the intermittent feed, means actuated by the upper sprocket for releasing the latch upon the formation of loops of predetermined lengths, and a spring for restoring the arm to normal position.

This specification signed and witnessed this 21st day of December, A. D. 1914.
